(57) **CLAIM**

The ornamental design for a mounting device with ball, as shown and described.

DESCRIPTION

FIG. 1 is a front left perspective view showing a mounting device with ball, according to the invention;

FIG. 2 is a front right perspective view showing the mounting device with ball of FIG. 1;

FIG. 3 is a back right perspective view showing the mounting device with ball of FIG. 1;

FIG. 4 is a back left perspective view showing the mounting device with ball of FIG. 1;

FIG. 5 is a back elevational view showing the mounting device with ball of FIG. 1; and,

FIG. 6 is a front elevational view showing the mounting device with ball of FIG. 1.

The broken line showing of the screw heads illustrates the environment of the claimed design and forms no part thereof.
